(57) **CLAIM**

The ornamental design for a photo panel, as shown and described.

DESCRIPTION

FIG. 1 is a perspective view of a photo panel embodying the design;

FIG. 2 is a left and elevational view thereof;

FIG. 3 is a top plan view thereof;

FIG. 4 is a bottom plan view thereof;

FIG. 5 is a front elevational view thereof; and,

FIG. 6 is a rear elevational view thereof.

The broken lines shown in the drawings are illustrative only of a hanger/fastener for the photo panel and do not form a portion of the invention.
